Lora Graentzdoerffer(57) **ABSTRACT**

A retail shower door display assembly is provided with a point-of-sale display unit sized to be received within a retail store aisle. A first array of shower door glass panes is oriented within the display unit. Each shower door glass pane of the first array has a height, a thickness and a width. A second array of shower door glass panes is oriented within the display unit. Each shower door glass pane of the second array has a height, a thickness and a width that is different than the width of the first array of shower door glass panes. An array of shower door tracks is oriented within the display unit. Each shower door track of the array has a common length. An array of towel bars is oriented within the display unit. Each towel bar of the array has a common length.

TECHNICAL FIELD

Various embodiments relate to shower door assemblies; retail displays for displaying shower door assemblies; methods for manufacturing shower door components; and methods for installing shower door assemblies.

BACKGROUND

The prior art has provided shower door assemblies that are assembled and packaged for retail.

SUMMARY

According to at least one embodiment, a retail shower door display assembly is provided with a point-of-sale display unit sized to be received within a retail store aisle. A first array of shower door glass panes is oriented within the display unit. Each shower door glass pane of the first array has a height, a thickness and a width. A second array of shower door glass panes is oriented within the display unit. Each shower door glass pane of the second array has a height, a thickness and a width that is different than the width of the first array of shower door glass panes. An array of shower door tracks is oriented within the display unit. Each shower door track of the array has a common length.

According to at least one embodiment, a method of installing a shower door assembly provides at least one shower door track from an array of shower door tracks oriented within a point-of-sale display unit sized to be received within a retail store aisle of a retail shower display assembly, wherein each shower door track of the array has a common length. The at least one shower door track is installed. At least one shower door glass pane is provided from one of a first array of shower door glass panes oriented within the display unit, and a second array of shower door glass panes oriented within the display unit. Each shower door glass pane of the first array has a height, a thickness and a width. Each shower door glass pane of the second array has a height, a thickness and a width that is different than the width of the first array of shower door glass panes. The at least one shower door glass pane is installed to the at least one shower door track.

According to at least another embodiment, a retail shower door display assembly is provided with a point-of-sale display unit sized to be received within a retail store aisle. A first array of shower door glass panes is oriented within the display unit. Each shower door glass pane of the first array has a height, a thickness and a width. A second array

2

of shower door glass panes is oriented within the display unit. Each shower door glass pane of the second array has a height, a thickness and a width, at least one of the height and the width is different than that of the first array of shower door glass panes. An array of towel bars is oriented within the display unit. Each towel bar of the array has a common length.

According to at least another embodiment, a method of installing a shower door assembly provides at least one shower door glass pane from one of a first array of shower door glass panes and a second array of shower door glass panes oriented within a point-of-sale display unit sized to be received within a retail store aisle of a retail shower door display assembly. Each shower door glass pane of the first array has a height, a thickness and a width. Each shower door glass pane of the second array has a height, a thickness and a width that is different than the width of the first array of shower door glass panes. At least one towel bar is provided from an array of towel bars oriented within the display unit. Each towel bar of the array has a common length. The at least one towel bar is installed to the at least one shower door glass pane.

According to at least one embodiment, a method of manufacturing shower door components is provided by forming a first plurality of shower door glass panes, each with a height, a thickness and a width. An aperture pattern is formed in each of the first plurality of shower door glass panes to mount a towel bar to the aperture pattern. Each of the first plurality of shower door glass panes is tempered after the aperture pattern is formed. A second plurality of shower door glass panes is provided, each with a height, a thickness and a width that is different than the width of the first plurality of shower door glass panes. An aperture pattern is formed in each of the second plurality of shower door glass panes to mount a towel bar to the aperture pattern. Each of the second plurality of shower door glass panes is tempered after the aperture pattern is formed. A plurality of towel bars is provided, having a common mounting pattern to mount to the aperture pattern in the first plurality of shower door glass panes and the second plurality of shower door glass panes.

According to an embodiment, a shower door assembly is manufactured according to a method of manufacturing shower door components by forming a first plurality of shower door glass panes, each with a height, a thickness and a width. An aperture pattern is formed in each of the first plurality of shower door glass panes to mount a towel bar to the aperture pattern. Each of the first plurality of shower door glass panes is tempered after the aperture pattern is formed. A second plurality of shower door glass panes is provided, each with a height, a thickness and a width that is different than the width of the first plurality of shower door glass panes. An aperture pattern is formed in each of the second plurality of shower door glass panes, common to the aperture pattern formed in the first plurality of shower door glass panes, to mount a towel bar to the aperture pattern. Each of the second plurality of shower door glass panes is tempered after the aperture pattern is formed. A plurality of towel bars is provided, having a common mounting pattern to mount to the aperture pattern in the first plurality of shower door glass panes and the second plurality of shower door glass panes.

According to another embodiment, a shower door assembly is manufactured according to a method of manufacturing shower door components by forming a first plurality of shower door glass panes, each with a height, a thickness and

a width. An aperture pattern is formed in each of the first plurality of shower door glass panes to mount a towel bar to the aperture pattern. Each of the first plurality of shower door glass panes is tempered after the aperture pattern is formed. A second plurality of shower door glass panes is provided, each with a height, a thickness and a width that is different than the width of the first plurality of shower door glass panes. An aperture pattern is formed in each of the second plurality of shower door glass panes, common to the aperture pattern formed in the first plurality of shower door glass panes, to mount a towel bar to the aperture pattern. Each of the second plurality of shower door glass panes is tempered after the aperture pattern is formed. A plurality of towel bars is provided, having a common mounting pattern to mount to the aperture pattern in the first plurality of shower door glass panes and the second plurality of shower door glass panes. A plurality of shower door tracks are formed each having a common length.

BRIEF DESCRIPTION OF THE DRAWINGS

FIG. 1 is a perspective view of retail shower door display system according to an embodiment;

FIG. 2 is a front perspective view of a retail shower door display assembly of FIG. 1;

FIG. 3 is an enlarged front perspective view of signage of the retail shower door display assembly of FIG. 2; and

FIG. 4 is a front perspective view of another retail shower door display assembly of FIG. 1.

DETAILED DESCRIPTION

As required, detailed embodiments of the present invention are disclosed herein; however, it is to be understood that the disclosed embodiments are merely exemplary of the invention that may be embodied in various and alternative forms. The figures are not necessarily to scale; some features may be exaggerated or minimized to show details of particular components. Therefore, specific structural and functional details disclosed herein are not to be interpreted as limiting, but merely as a representative basis for teaching one skilled in the art to variously employ the present invention.

Conventional shower door assemblies are typically retailed pre-bundled or prepackaged. Conventional shower door assemblies typically include shower door glass panes, shower door tracks, and shower hardware assemblies. The preassembled retail of these assemblies limits consumer options, while providing an overall unit that is relatively large and consequently difficult to transport from the point-of-sale to the point of installation. The preassembled unit may also be difficult to install.

Conventional shower door assemblies are often provided in varying sizes and styles. Therefore, for each style, shower door glass panes, shower door tracks, and towel bars are often provided specific to each standard sized for the shower door assemblies. All of the components required for the varying sizes and styles results in a large number of components to manufacture and retail.

Referring now to FIG. 1, a retail shower door display system is illustrated according to an embodiment, and referenced generally by numeral 20. The display system 20 is provided by, for example, a pair of retail shower door display assemblies 22, 24. The display system 20 is sized to be displayed within a retail store aisle, such as a home improvement store. The display system 20 is utilized for both displaying and retailing shower door components.

Shower door assemblies are conventionally categorized by function or type. For example, shower door assemblies include sliding shower door assemblies 26 and pivoting shower door assemblies 28. The first decision a consumer of shower door assemblies may need to decide is which style or category 26, 28 of shower door assembly is desired. Once the consumer selects a category 26, 28, the consumer may approach the corresponding display assembly 22, 24.

The retail shower door display system 20 includes a pair 10 of point-of-sale display units 30, 32. Of course, any number of point-of-sale display units is contemplated; and as will be explained, it is advantageous to provide the greatest variety of products per each point-of-sale display unit 30, 32. The point-of-display units 30, 32 are sized to be received within 15 a retail store aisle; and may be sized the same as conventional shelving for preassembled doors for easy replacement.

The sliding shower door assembly 26 includes an array of shower door glass panes 34, which may be for sliding tub doors, for example. The shower door glass panes 34 may 20 vary in style. The shower door glass panes 34 each have a standard height, a standard thickness, and a standard width for that application. An array of shower door tracks 36 is provided in the display unit 30 with standard dimensions for the sliding tub door application. The tracks 36 may also vary 25 in style. The separate packaging permits the customer to select from a large combination of varieties due to the interchangeability of the glass panes 34 and the tracks 36. The tracks 36 depicted are guide tracks 36 for sliding a pair of shower door glass panes 34 within the guide tracks 36. 30 Alternatively to, or in addition to, the tracks 36 may be frames for the shower door glass panes 34.

The sliding shower door assemblies 26 also include an array of shower door glass panes 38 for sliding shower doors. The shower door glass panes 38 include a standard 35 height, which is typically greater than that for a sliding tub door. The shower door glass panes 38 have a standard thickness, and a standard width, for example, to span up to a forty-eight inch shower door opening. Another array of shower door glass panes 40 is provided similar to the shower 40 door glass panes 38, except, the second array of sliding shower doors glass panes 40 have a greater standard width, such as to span up to a sixty inch shower door opening.

The sliding shower door assemblies 26 include an array of shower door tracks 42 for a sliding shower doors, which 45 according to one embodiment all have a common length only, for example the greater of the standard shower door opening size of sixty inches. According to another embodiment, the array may include sets of tracks 42 in a first length, such as forty-eight inches and sets of tracks 42 in a second length, such as sixty inches. The array of shower door tracks 42 may include shower door tracks in various finishes, such as chrome, nickel and bronze. No other tracks are provided for sliding shower doors to minimize space occupied in the display unit 30. A customer requiring a shorter track purchases one of the tracks 42; and shortens the track 42 prior to installation. By providing only one track size for different size shower door glass panes 38, 40 manufacturing costs are lowered, providing a cost-savings to the end customer, while reducing space required in the display unit 30.

Next, an array of towel bars 44 is oriented within the display unit 32. Each towel bar 44 of the array has a common length. Additionally, each towel bar 44 has a common mounting pattern. Likewise, each of the shower door glass panes 34, 38, 40 each have a common aperture pattern that corresponds to the common mounting pattern of the towel bars 44. By providing one standardized towel bar 44 size, various combinations with each of the shower door glass

panes 34, 38, 40 can be achieved while providing a vast reduction to shelf space. In order to meet this end, the aperture patterns are formed in the glass panes 34, 38, 40 prior to tempering. By standardizing the aperture patterns, manufacturing costs are also minimized.

The retail shower door display system 20 also includes signage 46 for explaining the sequence for a customer to select the components for a shower door assembly 26, 28. The glass panes 34, 38, 40 are provided sequentially prior to the tracks 36, 42 because customers typically select the glass panes 34, 38, 40 first since it is the largest aesthetic and functional component of the assembly 26, 28.

The display unit 32 also includes a pair of arrays of shower door glass panes 48, 50 for pivoting shower door assemblies 28 in two standard sizes, such as thirty-one inches and thirty-six inches by way of example. A pair of arrays of shower tracks 52, 54 for the pivoting shower door assemblies 28 are also provided in the two standard sizes. An array of pull handles 56 is provided for use with the various shower door glass panes 48, 50. Signage is provided to explain the sequence for selecting components.

The retail shower door display system 20 provides a large variation of shower door assemblies 26, 28 without limits provided in prepackaged assemblies. Interchangeability of tracks 36, 42, 52, 54, towel bars 44 and pull handles 56 further saves shelf space. The pull handles 56 are provided in multiple finishes, such as chrome, nickel and bronze, and are sized to be mounted to either size glass pane 48, 50. In the depicted embodiment, 183 combinations are provided in less than two display units 30, 32, which if prepackaged as in the prior art, would require almost eight display units.

The retail shower door display system 20 allows the consumer to custom configure a shower door based on the consumer's selection. The retail shower door display system 20 enables the consumer to mix and match style, finish, and glass textures for a customized sliding-tub shower door assembly 26, sliding shower door assembly 26 or a pivot shower door assembly 28. The retail shower door display system 20 permits the manufacturer to retail more Stock Keeping Units (SKUs) in the retail shower door display system 20 than would be practical with traditional preassembled and prepackaged shower door assemblies. The consumer can avoid having to lift, carry and transport a single total weight package due to the separation of the components. Consumers can also more readily transport components in vehicles due to an ability to place each packaged component in a vehicle interior and trunk due to separate packaging. Also, the customer can purchase replacement parts without a need to replace an entire shower door assembly in case of component repair when a specific component requires replacement, but the entire assembly does not require replacement. The customer can purchase replacement parts for new remodeling efforts where a glass or frame finish change is desired. The customer can purchase replacement parts for future product maintenance when one or more components require replacement due to wear or damage.

The manufacturer can also avoid steps of shipping the components to a common facility for assembling and packaging. The manufacturer can also more readily maintain inventory; easily add new products to the retail shower door display system 20; and regionalize the product mix.

While various embodiments are described above, it is not intended that these embodiments describe all possible forms of the invention. Rather, the words used in the specification are words of description rather than limitation, and it is understood that various changes may be made without

departing from the spirit and scope of the invention. Additionally, the features of various implementing embodiments may be combined to form further embodiments of the invention.

5

What is claimed is:

1. A shower door retail comprising:
a first array of separately packaged shower door glass panes, each shower door glass pane of the first array having a height, a thickness, and a width for a first shower door opening;

a second array of separately packaged shower door glass panes, each shower door glass pane of the second array having a height, a thickness, and a width for a second shower door opening that is different than the width of the first array of shower door glass panes; and

an array of shower door tracks, each shower door track of the array sized for a shower door opening that is the larger of the first shower door opening and the second shower door opening, wherein each shower door track of the array of shower door tracks is packaged separately from the first array of separately packaged shower door glass panes, and wherein each shower door track of the array of shower door tracks is packaged separately from the second array of separately packaged shower door glass panes.

2. The shower door retail of claim 1 wherein the width of the second array of shower door glass panes is greater than the width of the first array of shower door glass panes; and wherein each shower door track of the array of shower door tracks is sized for the second shower door opening.

3. The shower door retail of claim 2 wherein the array of shower door tracks is adapted to be shortened to correspond to the first shower door opening.

4. The shower door retail of claim 2 wherein the first array of shower door glass panes is sized to span a forty-eight inch shower door opening.

5. The shower door retail of claim 2 wherein the second array of shower door glass panes are sized to span a sixty inch shower door opening.

6. The shower door retail of claim 1 wherein a length of each of the array of shower door tracks is greater than forty-eight inches.

7. The shower door retail of claim 1 wherein a length of each of the array of shower door tracks is sized for a sixty inch shower door opening.

8. The shower door retail of claim 2 further comprising an array of towel bars, each towel bar of the array having a common mounting pattern.

9. The shower door retail of claim 8 wherein the array of towel bars is packaged separately from the array of shower door tracks.

10. The shower door retail of claim 9 wherein the first and second arrays of shower door glass panes, the array of shower door tracks, and the array of towel bars are oriented sequentially for user selection of a shower door glass pane first, a shower door track second, and subsequently a towel bar.

11. The shower door retail of claim 10 further comprising signage to explain a sequence for a customer to select components.

12. The shower door retail of claim 1 wherein an aperture pattern is formed in each of the first array of shower door glass panes to mount a towel bar to the aperture pattern.

65

13. The shower door retail of claim 12 wherein an aperture pattern is formed in each of the second array of shower door glass panes to mount a towel bar to the aperture pattern.

14. The shower door retail of claim 13 wherein the aperture pattern formed in the first array of shower door glass panes corresponds to the aperture pattern formed in the second array of shower door glass panes.

15. The shower door retail of claim 14 further comprising an array of towel bars, each towel bar of the array having a mounting pattern to mount to the aperture pattern of the first and second arrays of shower door glass panes.

16. The shower door retail of claim 1, wherein the shower door glass panes of the first array are separately packaged by presenting the shower door glass panes of the first array in an upright orientation in a display unit; and

wherein the shower door glass panes of the second array are separately packaged by presenting the shower door glass panes of the second array in an upright orientation in the display unit.

17. The shower door retail of claim 16, further comprising an array of towel bars;

wherein towel bars of the array each have a common length and a common mounting structure;

wherein the shower door glass panes of the first array and the shower door glass panes of the second array each have a common aperture pattern; and

wherein the common mounting structure is corresponding to the common aperture pattern.

18. The shower door retail of claim 17 further comprising signage having indicia for a sequenced selection from among the shower door glass panes of the first array, the shower door glass panes of the second array, the array of shower door tracks, and the array of towel bars.

19. A shower door assembly display system comprising the shower door retail of claim 1, and further comprising:

a third array of shower door glass panes presented in an upright orientation in the display system and sized for a third shower door opening having a third width and a third height;

a fourth array of shower door glass panes presented in an upright orientation in the display system and sized for a fourth shower door opening;

a second array of shower door tracks presented in the display system sized for the third shower door opening;

a third array of shower door tracks presented in the display system sized for the fourth shower door opening;

an array of towel bars and/or pull handles presented in the display system having a common length and a common mounting structure, wherein at least the third array of shower door glass panes and the fourth array of shower door glass panes have a common aperture pattern corresponding to the common mounting structure; and

signage indicating configuring a shower door assembly by selecting from among any of the first array of shower door glass panes, the second array of shower door glass panes, the third array of shower door glass panes and the fourth array of shower door glass panes, the array of shower door tracks, the second array of shower door tracks, the third array of shower door tracks, and the array of towel bars and/or pull handles.

20. The shower door assembly display system of claim 19, wherein the third array of shower door glass panes and the fourth array of shower door glass panes comprise a plurality of glass design styles.

21. The shower door assembly display system of claim 20, wherein the second array of shower door tracks and the third array of shower door tracks comprise a plurality of material finishes and a plurality of design styles; and

5 wherein the array of towel bars and/or pull handles comprises a plurality of material finishes and a plurality of design styles.

22. The shower door assembly display system of claim 21 wherein the third width is approximately 48 inches.

10 23. The shower door assembly display system of claim 22 wherein the third shower door opening is a tub shower door opening.

15 24. The shower door assembly display system of claim 23 wherein the fourth shower door opening is a sliding shower door opening without a tub.

25 25. The shower door assembly display system of claim 21 wherein the third width is approximately 60 inches.

20 26. The shower door assembly display system of claim 25 wherein the third shower door opening is a tub shower door opening.

27. The shower door assembly display system of claim 26 wherein the fourth shower door opening is a sliding shower door opening without a tub.

28. A shower door retail comprising:
25 a first array of separately packaged shower door glass panes, each shower door glass pane of the first array having a height, a thickness, and a width;
a second array of separately packaged shower door glass panes, each shower door glass pane of the second array having a height, a thickness, and a width that is different than the width of the first array of shower door glass panes; and

30 an array of towel bars, each towel bar of the array having a common mounting pattern;

wherein an aperture pattern is formed in each of the first array of shower door glass panes to mount one towel bar from the array of towel bars to the aperture pattern; wherein an aperture pattern is formed in each of the second array of shower door glass panes to mount one towel bar from the array of towel bars to the aperture pattern; and

35 wherein the aperture pattern formed in the first array of shower door glass panes corresponds to the aperture pattern formed in the second array of shower door glass panes.

29. A shower door retail comprising:
a first array of separately packaged shower door glass panes, each shower door glass pane of the first array having a height, a thickness, and a width;

40 a second array of separately packaged shower door glass panes, each shower door glass pane of the second array having a height, a thickness, and a width that is different than the width of the first array of shower door glass panes; and

45 an array of towel bars, each towel bar of the array having a common mounting pattern;

wherein the width of the first array of separately packaged shower door glass panes is sized for a first shower door opening;

50 wherein the width of the second array of separately packaged shower door glass panes is sized for a second shower door opening that is different than the first shower door opening; and

55 wherein the shower door retail further comprises an array of shower door tracks, each shower door track of the array is sized for a shower door opening that is the larger of the first shower door opening and the second

US 12,144,441 B2

9

shower door opening, and each shower door track of
the array of shower door tracks is packaged separately.
